Att'ys.

UNITED STATES PATENT OFFICE.

JAMES H. RAND, OF NORTH TONAWANDA, NEW YORK, ASSIGNOR, BY MESNE ASSIGNMENTS, TO REMINGTON RAND INC., OF TONAWANDA, NEW YORK, A CORPORATION OF DELAWARE.

INDEX DEVICE.

Application filed December 18, 1924. Serial No. 756,681.

This invention relates to card indexes and more particularly to card indexes of the type in which a plurality of units are mounted in an upright frame in overlapping relationship so that the lower margins of the cards are visible and so that the cards may be swung apart to display the data on the overlapping portions, and objects of the invention are to provide an index device having 10 the new and improved features of construction and arrangement hereinafter described.

The invention is illustrated in one of the preferred forms in the accompanying drawings in which:

15 Fig. 1 is a face view of an index unit constructed in accordance with the invention;

Fig. 2 is a fragmentary view of the unit with the card removed; and

20 Fig. 3 is an enlarged section on the line 3—3 of Fig. 1.

The embodiment of the invention illustrated comprises a card holder 1 of card-board or relatively stiff paper to the upper margin of which is flexibly connected a supporting rail 2 which projects beyond the ends of the holder and is adapted to extend into guide channels in a suitable supporting frame thereby to hold the unit in place. Detachably connected to the holder 1 is a sheet 30 3 which may be of relatively flexible paper or other suitable material, the upper margin of which extends slightly below the supporting rail 2 and the upper corners extending through diagonal slots 4 in the holder 1.

35 The lower margin of the sheet 3 is folded upon itself thereby providing an integral folded portion 5 extending substantially parallel to the sheet 3. Enclosing the folded margin of the sheet 3 and the margin of the holder 1 is a sheath 6 of transparent sheet material, such as celluloid, which is formed from a sheet of such material folded upon itself along one longitudinal margin to form front and rear walls which are yieldingly 40 urged toward each other owing to the resiliency of the material. The opposite ends of the front and rear walls of the sheath are fastened to the holder 1 by staples 7 thereby preventing relative movement between the sheath and holder. As indicated in Fig. 3

45 the folded portion 5 of the sheet 3 extends a slight distance above the sheath 6 and provides a pocket with the sheet for the reception of a card 8 which is shorter and of less

width than that of the holder 1 and a different height and width than sheet 3, thus to enable the card readily to be grasped for removal from the pocket, the upper corners of the card being adapted to extend into diagonal slots 4 in the holder 1. 55 60

In order visibly to indicate the presence or absence of the card 8 in the pocket without swinging one unit away from the adjacent unit, an aperture 9 on the folded portion 5 is arranged to register with an area 10 on the sheet 3 which area may be colored differently from the card 8. Thus, for example by coloring the area 10 black and the card 8 pink, the color pink will show through the opening 9 when the card is in place but when the 70 card is removed the color black will show through the opening. In this manner a user may quickly and easily determine the presence or absence of the card in the unit. 75

An index device of the character described may be used to advantage in a variety of situations. Thus, by way of example the card 8 may be used as a salesman's follow-up and report card which may be carried by salesmen when making a call upon a prospective customer, and may contain such indicia as fully to identify the prospect as well as the progress of the salesman with the prospect. The subject matter on this card may be copied on the sheet 3 so that when 80 the salesman's card is out the index still contains the desired information, this being particularly advantageous in the event of the salesman's card being lost or mislaid. The folded portion 5 of the sheet 3 may contain 85 suitable symbols indicative of the various articles on sale and a suitably colored signal 11 which may be of transparent sheet celluloid having an opening 12 may be placed over the symbol designating the particular article in which the prospect is interested. Thus, by glancing at the index the user will not only be informed as to the article in which the prospect is interested, but also whether the salesman is making a call. 90 95 100

A cardinal feature of the invention consists in the provision of the folded sheet which provides a pocket for the reception of an index card, the folded portion having indicia visible through the sheath so that when 105 a number of units are arranged in a spaced overlapping relation this indicia may readily be observed. The provision of the colored

area on the sheet is advantageous to signal the presence or absence of the card in the pocket without manipulation of the index.

While the index device herein shown and described is admirably adapted to fulfill the requirements, it is to be understood that it is not intended to confine the invention to the one form of embodiment herein disclosed, for it is susceptible to embodiment in various forms all coming within the scope of the claims which follow. The term colors is used in a broad sense to connote contrasting hues or shades whether actually colored or white, black, gray, etc.

15 I claim:

1. An index device comprising a card holder, a sheath of transparent sheet material enclosing a margin of said holder, and a sheet having a folded margin extending into said sheath, said folded portion and sheet forming a pocket for the reception of an index card.

2. An index device comprising a card holder, a sheath of transparent sheet material enclosing a margin of said holder, a sheet having a folded margin extending into said sheath, the free end of the folded portion extending a slight distance above the sheath.

3. An index device comprising a card holder, a sheath of transparent sheet material enclosing a margin of said holder, a sheet having a folded margin extending into said sheath, the folded portion and sheet forming a pocket, and a card in said pocket, said card being of less width than the sheet.

4. An index device comprising a card holder, a sheath of transparent sheet material enclosing a margin of said holder, a sheet having a folded margin extending into said sheath, said holder having slits to receive the corners of said sheet remote from said sheath, and a card extending into said sheath between the folded portions of said sheet, said card being of less width than the sheet.

5. An index device comprising a card holder, a sheath of transparent sheet material enclosing a margin of said holder, a sheet having a folded margin extending into said sheath forming a pocket, the front part of said folded portion having an aperture, a colored area on the rear part of said folded margin arranged to register with said aperture, and a card in said pocket, said card being colored differently from said colored area whereby the presence or absence of said card is visibly indicated through said aperture.

6. An index device comprising a card holder, a sheath of transparent sheet material enclosing a margin of said holder, a sheet having a folded margin extending into said sheath, the folded portion of said sheet extending a slight distance above said sheath and having an aperture visible through said sheath, a colored area on the sheet arranged to register with said aperture, and a card between said sheet and folded portion, said card being colored differently from said colored area thereby visibly to indicate through said aperture the presence or absence of said card.

7. An index device comprising a card holder, a sheath of transparent sheet material enclosing a margin of said holder, a sheet having a folded margin extending into said sheath, the folded portion of said sheet extending a slight distance above said sheath and having an aperture visible through said sheath, said holder having slits to receive the corners of said sheet remote from said sheath, a colored area on the sheet arranged to register with said aperture, and a card between said sheet and folded portion, said holder having slits to receive the corners of said card remote from said sheath, said card being colored differently from said colored area thereby visibly to indicate through said aperture the presence or absence of said card.

Signed by me at North Tonawanda, New York, this twelfth day of December, 1924.

JAMES H. RAND.
